[57] CLAIM

The ornamental design for a computer desk, as shown and described.

DESCRIPTION

FIG. 1 is a top, front perspective view of a computer desk showing our new design; the broken lines are for illustrative purposes only and form no part of the claimed design;

FIG. 2 is a front elevational view thereof;

FIG. 3 is a top plan view thereof;

FIG. 4 is a left side elevational view as seen when in use, the right side being a mirror image thereof;

FIG. 5 is a rear elevational view thereof; and,

FIG. 6 is a bottom plan view thereof.
